[57] CLAIM

The ornamental design for a sofa or similar article, substantially as shown and described.

DESCRIPTION

FIG. 1 is a perspective view of a sofa or similar article showing our new design;

FIG. 2 is a front elevational view thereof;

FIG. 3 is a top plan view thereof;

FIG. 4 is a rear elevational view thereof; and

FIG. 5 is a side elevational view thereof, the opposite side being substantially a mirror image thereof.

FIG. 1

FIG. 2

FIG. 3

FIG. 4

FIG. 5
